United States Patent Office.

EDWARD COTTER, OF BOSTON, MASSACHUSETTS.

Letters Patent No. 98,038, dated December 21, 1869.

IMPROVED COMBINATION OF PIANO-FORTE AND CABINET.

The Schedule referred to in these Letters Patent and making part of the same.

To all persons to whom these presents shall come:

Be it known that I, EDWARD COTTER, of Boston, county of Suffolk, and State of Massachusetts, have invented a certain new and useful Improved Combined Piano-Forte and Cabinet; and that the following is a full and exact description of the same, reference being had to the accompanying plates of drawings.

The present invention consists of a piano-forte, of the class known as square and cabinet, combined in one and the same piece or article of furniture, by constructing under the body of the piano-forte, and upon which it rests or is attached in any suitable manner, cases or closets, for the reception of books, sheets, or folios, relating to music, &c., with suitable doors thereto, for opening and closing the same to view, together with applying, to the back of the piano-forte body, a frame extending upward and above the same, of any suitable design and ornamentation, and provided with shelves, &c., for the reception of articles, such as vases, statuettes, and other ornaments or books, &c., and either with or without, as may be desired, a mirror or mirrors.

In the accompanying plates of drawings, my improved combined piano-forte and cabinet is illustrated.

In plate 1,

Figure 1 is a front elevation, with the piano and cases closed.

Figure 2, a horizontal section in plane of line $z z$, fig. 1.

In plate 2,

Figure 3 is a front elevation, with the piano-lid and case or closet-doors opened.

Figure 4, a transverse vertical section in the plane of the line $y y$, fig. 1.

A, in the drawings, represents the body of a piano-forte, of that class of the same known as a square.

This body, upon its interior, is to be constructed and provided with mechanism and devices for the production of musical sounds, in any of the ordinary modes now practised, and for the purpose of opening and closing the same, is provided with a top or lid, B, made in three sections or parts, C, D, and E, hinged together, and to the rear side of the body A.

F, an under-supporting frame-work for the body A, which, in lieu of being simply composed of legs, one at each corner, as heretofore, is made of a box-form, (see fig. 2, plate 1,) more particularly divided into at least two closets or cases, G and H, open upon the front side of the body A, and at such side each provided with a hinged door, I, for opening and closing their interior to view.

These closets, G and H, are located at each end of the body A; and between them, in the centre of the body, is a chamber, I², wherein is to be located the pedal-stand of the piano, in the usual manner.

This chamber may, or not, as desired, have a door for opening and closing the same at pleasure.

The closet G is provided with a series of horizontal partitions, forming shelves, L, and the closet H with vertical partitions, M, whereby they are adapted for the convenient reception of books, folios, and sheets of music, &c.

N, a frame, applied to rear side of body A, in any suitable manner, by dowel-pins and socket-screws, or otherwise, and extending upward therefrom in a vertical plane.

This frame N, in the present instance, at its centre, o, is cut out, for the reception of a mirror, and at several places is shown as provided with shelves, P, supported by brackets, Q, for the reception of vases, statuettes, books, and other ornaments.

In the manufacture of the said frame N, closets G and H, and body A, it is intended to ornament the same by mouldings, in any suitable manner.

From the above description of my invention, it is manifest that a most convenient, useful, serviceable, and desirable article of furniture is produced, combining in itself two now separate and distinct pieces, viz, a piano-forte and cabinet, and without sacrificing any of the features of the one or the other, possessed by it when made separate, such a combination economizing not only space in a room or apartment, but securing greater convenience by its compactness and general arrangement.

Having thus described my invention, I shall state my claim as follows:

What I claim as my invention, and desire to have secured to me by Letters Patent, is—

A "square" piano-forte, in combination with closets G and H, and upright extension-frame N, provided with shelves, when combined and arranged together, forming one piece of furniture, as and for the purpose described.

The above specification of my improved combined piano-forte and cabinet signed by me, this 20th day of October, A. D. 1869.

EDW: COTTER.
